UNITED STATES PATENT OFFICE.

CHARLES E. BRADSHAW, OF WATERBURY, CONNECTICUT, ASSIGNOR TO ROBERT N. BASSETT COMPANY, INCORPORATED, OF SHELTON, CONNECTICUT, A CORPORATION OF CONNECTICUT.

BUCKLE.

1,406,971.

Specification of Letters Patent. Patented Feb. 21, 1922.

Application filed July 17, 1918, Serial No. 245,323. Renewed December 22, 1921. Serial No. 524,298.

To all whom it may concern:

Be it known that I, CHARLES E. BRADSHAW, a citizen of the United States, residing at the city of Waterbury, in the county 5 of New Haven and State of Connecticut, have invented a certain new and useful Improvement in Buckles, of which the following is a specification.

My invention relates to buckles and other 10 mountings for running webbing of the class wherein the frame member is provided with inwardly projecting trunnions on which the lever member is pivotally supported, and its object is to provide a buckle of this 15 character having neat and compact pivotal connections designed to bear a severe strain when the buckle is closed on the webbing.

My invention consists in constructing a buckle of the class above mentioned in which 20 the inwardly projecting trunnions are disposed edgewise to the face portion of the back plate of the frame member instead of flatwise thereto, and the lever member is provided with apertured side ears which 25 receive these trunnions so that the strain on both the trunnions and side ears, which is exerted by the lever member when closing the buckle, is in the direction of the plane 30 of the trunnions and the plane of the side ears whereby both trunnions and side ears receive the strain upon their edges rather than upon their flat sides or face portions.

Other features of the invention will appear in the details of construction and manner of operation set forth in the following 35 description and accompanying drawings in which like reference characters refer to corresponding parts.

In the drawings:

- 40 Figure 1 is a perspective view of the buckle strung with webbing;
Figure 2, a side view;
Figure 3, a central, vertical, sectional view;
45 Figure 4, a top view before the webbing is attached thereto, and
Figure 5, a vertical sectional view of the parts shown in Figure 4 in their open position.
50 The buckle shown consists of a back member or frame A and a front member or lever B. The back member A is bent up out of a sheet metal blank to form the back plate 2 having its lower extremity provided with 55 a projecting lip 3 which is folded toward

the back plate and swedged on to the end *k* of the webbing C so that this end is confined between the lip and the face portion of the back plate as shown in Figure 3. The back plate 2 is also provided with forwardly turned side ears 4, 4 and projecting inwardly toward each other from the top edges respectively of these ears are the aligned pintles or trunnions 5, 5 which are disposed edgewise to the front face of the back plate and adjacent to the top side thereof so that the plane of the trunnions 5, 5 is substantially at right angles with the plane of the front face of the back plate. The lever B is also bent up out of a sheet metal blank to form the front portion or shield 6 having its upper extremity provided with the web-gripping portion or projecting shelf 7 disposed at an angle thereto. The front portion or shield 6 is also provided with the rearwardly turned side ears 8, 8 which are spaced from the side edges respectively of the shelf 7 and have their body portions provided with apertures 9, 9 through which are passed the inwardly projecting trunnions 5, 5, thereby forming a pivotal connection between the front and back members. While the buckle may be strung with webbing in any suitable manner, yet I prefer the rustless stringing, 85 so called because the back of the buckle, or the face portion thereof toward the body of the wearer when used on garments, is covered with webbing to prevent any moisture due to perspiration from coming in contact with the metal surface. After the extremity *k* is secured between the lip and the back plate in the manner described the free or moving portion of the webbing is 90 passed rearwardly over the top edge of the back plate, then downwardly below the back and then upwardly between the lever and back plate, forming an adjustable loop in the webbing carrying the cast-off member D, or any other suitable member. When 95 buckles are strung rustless to form an adjustable loop as described it is desirable that the pivotal connection between the lever and back should be located high up adjacent to the uppermost portion of the back in order to prevent the front layer of webbing from swinging away from the top edge of the back when the buckle is under stress. To bring the location of the pivotal connections to a position adjacent to the top edge 100 105 110

of the back I form the inwardly projecting trunnions on the top edges respectively of the side ears 3, 3 of the back member. The forming of the trunnions on the top edges 5 of the ears in this manner enables a blank to be used containing a minimum amount of metal, or at least no more metal than that required in the present style of back which is provided with apertured side ears for 10 trunnions located on the lever member and having its lower extremity below the ears formed with a projecting lip, such buckles being known as swedged lip buckles. In the blank required for forming the back of my 15 buckle before the trunnions and side ears are bent out of the plane of the back plate the lugs which form the trunnions project upwardly on each side of the metal forming the lip in the preceding blank so that the scrap 20 left at the sides of the lip can be utilized in forming the trunnions thus the same number of blanks can be sheared out of the same length of metal strip as is now employed in the present style of swedged lip buckles 25 above referred to. The side ears on the lever member are spaced apart a distance slightly less than that between the side ears on the back member so that when the parts are assembled the ears on the lever are 30 closely embraced by the ears on the back leaving sufficient clearance, however, to enable the pivotal action to take place when the buckle is opened and closed. This close engagement between the side ears on the 35 respective members causes the strain on the trunnions which is exerted by the lever member when the buckle is closed to be received at the base of the trunnions, that is, where they are joined onto the side ears of the 40 back member, rather than throughout their length or towards their extremities, as is usually the case in the present style of buckles having inwardly projecting trunnions. Locating the strains at the base of 45 the trunnions and on their edges instead of on their face portions enables me to employ not only short trunnions but also to form the back out of a lighter gauge of metal than is required in the present style 50 of buckle having inwardly projecting trunnions. This feature, taken together with the feature of embodying my invention in a swedged lip buckle, is very desirable since the swedged lip buckles may also be formed 55 out of a lighter gauge metal than other styles of buckles. It should be observed that in the preferred buckle disclosed I am enabled to locate the shelf or web-gripping member of the lever in a position where it 60 will intersect the plane of the trunnions when the buckle is opened and closed, but in no way interfering with the trunnions which project into the spaces formed between the side edges of the shelf and the 65 adjacent side ears on the lever member,

This location of the shelf can not be obtained in a buckle wherein the trunnions are extended until they meet in the form of a bar disposed across the front of the back member nor in a buckle wherein the trunnions are journaled in sleeves or pintle straps rolled on the lever member beyond the side edges of the shelf. Further, the use of trunnions of minimum length enables a shelf of greater width to be employed, that is, a shelf which presents a longer gripping edge to the webbing.

Wherever I have used the term back member it is to be understood that I refer to that part of the buckle with which the lever cooperates and which is not necessarily the back portion of the buckle since the device may be used in such a way that the lever member might be regarded as the back member of the buckle. While the device above described is the preferred embodiment of my invention yet it is understood that the same is susceptible to such modification as may fairly come within the scope of the appended claims.

Having now described my invention what I claim and desire to protect by Letters Patent is:

1. A buckle comprising a sheet metal back having forwardly turned side ears the upper edges of which are provided with inwardly projecting trunnions disposed in a plane at substantially right angles to the face portion of the back, and a lever member pivotally mounted on said trunnions.

2. A buckle comprising a sheet metal back having forwardly turned side ears the top edges of which are provided with inwardly projecting trunnions and a sheet metal lever having rearwardly turned side ears provided with apertures in which said trunnions are journaled.

3. A sheet metal buckle for running webbing comprising a back having forwardly turned side ears the top edges of which are provided with inwardly projecting trunnions disposed in a plane substantially at right angles with the front face of the back, and a lever member having rearwardly turned side ears which are closely embraced by the side ears on the back provided with apertures in which the trunnions are journaled.

4. A sheet metal buckle for running webbing comprising a back provided with a web-holding lip and forwardly turned side ears the upper edges of which are provided with inwardly projecting trunnions formed integral therewith, and a lever member pivotally mounted on said trunnions.

5. A sheet metal buckle for running webbing comprising a back having a web-holding lip at its lower extremity and forwardly turned side ears the top edges of which latter are provided with inwardly projecting

trunnions disposed in a plane substantially at right angles with the front face of the back, and a lever member having rearwardly turned side ears which are closely embraced by the side ears on the back and which are provided with apertures in which the trunnions are journalled.

6. A sheet metal buckle for running webbing comprising a back having a web-holding lip at its lower extremity and forwardly turned side ears the top edges of which are provided with inwardly projecting trunnions disposed in a plane substantially at right angles with the front face of the back, and a lever member having rearwardly turned side ears which are closely embraced by the side ears on the back and provided with apertures in which the trunnions are journalled and a shelf which swings through the axis of said trunnions during the movement between the lever and back, the said

shelf being cut away at its extremities to make room for the inwardly projecting trunnions on the back.

7. A sheet metal buckle for running webbing comprising a back having a web-holding lip at its lower extremity and forwardly turned side ears the top edges of which are provided with inwardly projecting trunnions disposed in a plane which passes through the top edge of the back, and a lever member having rearwardly turned side ears which are closely embraced by the side ears on the back and provided with apertures in which the trunnions are journalled, the said lever member also having a shelf which is disposed in a plane substantially at right angles with the front face of the back when the buckle is closed.

In testimony whereof I have hereunto set my hand this 27th day of June, 1918.

CHARLES E. BRADSHAW.
